PACKAGING CONTAINER OR THE LIKE

Stafford D. Collie, Kansas City, Mo., assignor to Phillips Petroleum Company, a corporation of Delaware

Filed June 23, 1967, Ser. No. 7,585

Term of patent 14 years

(Cl. D9—242)

FIGURE 1 is a perspective view of a packaging container or the like showing my new design;

FIGURE 2 is a side elevational view thereof, the side opposite being identical thereto;

FIGURE 3 is an end elevational view thereof, the end opposite being identical thereto; and

FIGURE 4 is a bottom plan view thereof.

The dominant features of my design reside in the portion shown in full lines, a conventional flange and stacking lugs being shown in broken lines.

I claim:

The ornamental design for a packaging container or the like, as shown and described.
